UNITED STATES PATENT OFFICE

2,051,490

DESK

Leo J. Lightfoot, Grand Rapids, Mich., assignor
to American Seating Company, Grand Rap-
ids, Mich., a corporation of New Jersey

Application June 14, 1935, Serial No. 26,586

5 Claims. (Cl. 45—91)

The instant invention relates to desks and more particularly to desks having a top portion which is adjustably tiltable and which is forwardly and rearwardly adjustably slidable.

5 The structure of the instant invention is of the general character shown in United States Letters Patent No. 2,016,571, issued October 8, 1935, on application filed December 24, 1934, by Glenn J. Barrett and by him assigned to my 10 assignee.

The primary objects of the present invention are to provide a structure of the general character above indicated which is particularly well adapted for use in the school room; to provide 15 such a structure whose desk top is amply adjustable both forwardly and rearwardly as well as upwardly and downwardly; to provide such a structure whose use by the school pupil is designed to economize eye strain; to provide such 20 a structure having means for maintaining the desk top in angularly adjusted position; to provide such a structure having means for releasing the desk top from locked angularly adjusted position; to provide such a structure whose desk 25 top serves as a lid for the book compartment of the desk; and, to provide such a structure which is utilitarian in use and economical in manufacture.

Illustrative embodiments of the invention are 30 shown in the accompanying drawings, wherein:

Figure 1 is a fragmentary perspective view of a school desk showing the desk top in one of its angularly adjusted positions;

Figure 2 is a side elevational view of the school 35 desk showing in dotted lines the desk top in two of its slid and angularly adjusted positions;

Figure 3 is an enlarged sectional view of the mechanism for maintaining the desk top in angularly adjusted position together with means 40 for locking the desk top in angularly adjusted position and for releasing the desk top from such angularly adjusted position, the section being on line 3—3 of Figure 4;

Figure 4 is a sectional view thereof on line 45 4—4 of Figure 3;

Figure 5 is a sectional view on line 5—5 of Figure 6;

Figure 6 is a sectional view thereof on line 50 6—6 of Figure 3;

Figure 7 is a sectional view on line 7—7 of Figure 3; and

Figure 8 is a fragmentary top plan view of the school desk showing the cover in upwardly 55 tilted position.

Referring now to these drawings in which like parts of the structure shown are designated by the same numerals in the several views, a desk is here shown as of the school type with a conventional wooden or metal bottom 10, upstanding opposite ends 11, 12, and sides 13, 14 forming a book compartment or box. A pair of guide members 15, 16, here shown as metal rods, are respectively secured to the opposite ends 11, 12 along their respective outside surfaces and in 10 spaced relation thereto in any suitable manner as by brackets 17 best shown in Figure 3. A pair of plates 18, 19, preferably of stamped sheet metal, are provided with oppositely disposed depending tongues 20. The two tongues of each 15 plate are formed to slidably embrace rods 15, 16 respectively and an equalizing member 21 of considerable width is interposed between and secured to the inwardly flanged portion 22 of each plate 18, 19 in any suitable manner as by 20 screws 23.

Hinge members likewise of stamped sheet metal and each having depending segmental portions 26, 27 are respectively pivotally secured to the plates 18, 19 and each hinge member is provided with an inwardly flanged portion 28 to which the desk top 29 is secured as by screws 30.

The depending segmental portion 27 of the hinge member is provided with ratchet teeth 31 and a lever 32 interposed between the plate 19 and segmental portion 27 of the hinge member is pivotally secured to the plate 19 as by the pintle 33 and as best shown in Figure 3. This lever is provided with a curled projecting upper end extending through an opening of the cover 35 members 35 and forming a detent 34 adapted to be normally swung by the spring 36 into engagement with the ratchet teeth 31 for maintaining the desk top in angularly adjusted position as best shown in Figure 3 and as indicated in Figures 1 and 2. By manually shifting the detent 34 against the tension of the spring 36, it is released from the ratchet teeth 31 which lock the desk top 29 in adjusted angular position, permitting the desk top to drop.

Secured as by a rivet 38 to each plate 18, 19 on the outside thereof and adjacent the respective depending segmental portions 26, 27 of each hinge member is a friction disc 39 of raw hide or the like as best shown in Figure 4. The cover members 35 for each plate 18, 19 forming a housing for the hinge mechanism are each provided with a portion here shown as a friction disc 41 secured thereto as by the rivet 38 adapted to engage the respective depending segmental portions 26, 27 55

of the hinge members, likewise as best shown in Figure 4. These cover members 35 are preferably adjustably secured to the plates 18, 19 by screws 43 which adjustably control the tension of the discs 39, 41 on opposite sides of the depending segmental portions 26, 27 of the hinge members.

In operation, since the desk top 29 is hingedly connected to the plates 18, 19 which are slidably mounted upon the guide members or rods 15, 16, the desk top shown in full lines in Figure 2 may be raised and held in either of the adjusted angular positions by means of the ratchet and detent mechanism hereinbefore described and as shown in dotted lines in the same figure by either raising the desk top as thus indicated or by raising the desk top and sliding it forwardly as likewise indicated.

It will thus be seen that a desk top here shown as of the school type has been herein illustrated and described whose use tends to minimize eye strain and whose top alone serves as a book compartment of the desk.

While but one specific embodiment of the invention has been herein shown and described, it will be understood that numerous details of the construction shown may be altered or omitted without departing from the spirit of this invention as defined by the following claims.

I claim:

- 30 1. In a structure of the class described, a desk top support having parallel guide members disposed adjacent opposite ends thereof, a plate slidably secured to each guide member, a hinge member pivotally secured to each plate, and a desk top secured to the hinge members, one of said hinge members having a segmental portion, and spring tensioned means normally urged against the segmental portion for maintaining the desk top in angularly adjusted position.
- 35 2. In a structure of the class described, a desk top support having parallel guide members disposed adjacent opposite ends thereof, a plate slid-

ably secured to each guide member, a hinge member pivotally secured to each plate, and a desk top secured to the hinge members, one of said hinge members having a segmental portion, and a spring tensioned lever normally urged against the segmental portion for maintaining the desk top in angularly adjusted position.

3. In a structure of the class described, a desk top support having parallel guide members disposed adjacent opposite ends thereof, a plate slidably secured to each guide member, a hinge member pivotally secured to each plate, and a desk top secured to the hinge members, one of said hinge members having a segmental portion provided with ratchet teeth, and spring tensioned means secured to the plate adjacent the segmental portion adapted to normally engage said ratchet teeth for maintaining the desk top in angularly adjusted position.

4. In a structure of the class described, a desk top support having parallel guide members disposed adjacent opposite ends thereof, a plate slidably secured to each guide member, a hinge member pivotally secured to each plate, and a desk top secured to the hinge members, one of said hinge members having a segmental portion provided with ratchet teeth and spring tensioned means normally urged into engagement with said ratchet teeth for maintaining the desk top in angularly adjusted position.

5. In a structure of the class described, a desk top support having parallel guide members disposed adjacent opposite ends thereof, a plate slidably secured to each guide member, a hinge member pivotally secured to each plate, and a desk top secured to the hinge members, one of said hinge members having a segmental portion provided with ratchet teeth, and a spring tensioned lever normally urged into engagement with said ratchet teeth for maintaining the desk top in angularly adjusted position.

LEO J. LIGHTFOOT.
